PUMPING UNIT

Bee Henderson, Dryden, Tex.

Original application April 7, 1941, Serial No. 387,304. Divided and this application March 16, 1943, Serial No. 479,365

2 Claims. (Cl. 103—181)

My invention relates to improvements in well pumping means of the type featured in my co-pending application, Serial No. 387,304, filed April 7, 1941, now Patent No. 2,316,429, and of which the instant application is a division.

The principal object of the instant invention is to provide an inverted cylinder pumping unit designed for operation by a cable, as a power transmitting medium, instead of rods, and which utilizes the weight of the liquid being pumped for returning the pumping pistons, is simple in construction and highly efficient in operation.

Other objects and advantages, together with the precise nature of my improvements, will be readily understood when the succeeding description and claims are read with reference to the drawings accompanying and forming part of this specification.

In said drawings:

Figure 1 is a view in vertical section of the lower part of a well casing and the upper and lower portions of my improved pumping unit.

Figure 2 is a similar fragmentary view drawn to an enlarged scale.

Figure 3 is another similar fragmentary view taken through the lower portion of the well casing and pumping unit and drawn to a further enlarged scale.

Figure 4 is a view in transverse section taken on the line 4—4 of Figure 1 and drawn to an enlarged scale.

Figure 5 is a similar view taken on the line 5—5 of Figure 1.

Figure 6 is a view in perspective of one of the compression cup dividers drawn to an enlarged scale, and

Figure 7 is a fragmentary view in side elevation of the compression cup holder of the lower portion of the unit.

Reference being had to the drawings by numerals, the well casing 5, according to my invention, has threaded thereon a tapering, tubing compression cup holder 6 at the lower end thereof against which bears the bottom compression cup 7 which is tapered in conformity with the cup holder 6 and engages the lower end of the casing 5. The compression cup 7 spacedly surrounds a beveled annulus 8 engaging the lower end of the lower pump cylinder, designated 9, and rests on the horizontal flange 10 of said cup 7, as best shown in Figure 3. The flange 10 rests on a beveled lateral annular flange 11 formed on the lower end of the compression cup retainer 12 which is threaded into the lower end of the lower barrel 9 of the pump.

The upper end of the lower pump barrel 9 is threaded on the lower part of the splice sleeve 13 on whose upper part is threaded the slotted tubing 14 provided with the circumferentially spaced, vertically elongated openings 15. The upper end of the slotted tubing 14 is threaded on the lower part of the divider 16 on whose upper part is threaded the lower end of the upper barrel 17 of the pumping unit.

10 The parts 18, 19, 20 and 21 comprise means for anchoring the pumping unit in the well casing 5 against upward movement therein while allowing downward movement thereof in said casing and need merely be identified in passing.

15 The operating cable 22 depends through the well casing from the surface machinery, not shown, and passes downwardly through the upper end of the upper barrel 17, said cable being connected at its lower end in the opening 23 in

20 the upper part of the inverted cup-shaped member 24 which forms the top of the upper pumping cylinder, generally designated 25, and which is threaded into the skirt of the element 24, as shown in Figure 2. The upper pumping cylinder

25 has a vertically movable spool check 26 therein, the bottom of the said cylinder being provided with a relatively large opening 27 tapped by a seat 28 with which the spool check 26 is adapted to engage in its depressed position to

30 close the opening 27. The lower part of the pumping cylinder 25 has a lateral annular flange 29 above which are stacked several sets of compression cup dividers 30 and compression cups 31 which slidably engage the interior wall of the

35 upper barrel 17. Threaded into the depending portion of the compression cup retainer flange 27 is the upper end of the valve holder 32 which is in the form of a cup providing a chamber below the bottom

40 of the pumping cylinder 25 for operation of another spool check valve 33 which, in its depressed position, rests on a seat 34 formed around the upper end of an axial opening 35 provided in the bottom of the holder 32, into the lower part of

45 which opens the upper end of a relatively small diameter tube 36 threaded into said holder. The holder 32 is provided with circumferentially spaced radial openings 37 in the side wall thereof. A similar but more elevated opening 26 is provided in the side wall of the upper pumping cylinder 25.

The aforesaid tube 36 slides downwardly through an axial opening 38 in the divider 16 and through compression cups and retainers 55 formed in a unit 39 and attached to the lower

end of the divider 16 within the slotted tubing 14.

The lower end of the said tube 36 is threaded into the hole 40 in the center of an inverted cup-shaped upper element 41 of the lower pumping piston designated 42. The skirt of the element 41 is threaded on the upper end of the compression cup holder 43 which is relatively large in diameter and tubular in form and is provided on its lower end with a lateral annular flange 44 exteriorly beveled, as indicated by numeral 45. The flange 44 supports above it, on the exterior of the compression cup holder 43, a series of compression cup dividers 46, and compression cups 47 which engage the interior of the lower cup barrel 9 above the compression cup retainer 12 at the lower end of the lower pumping barrel 9.

The construction and arrangement of parts described above define chambers 50 and 51 located above and below the divider 16, respectively, within the lower part of the upper pump barrel 17, and the chamber defined within the upper barrel 17 above the upper pumping piston and directly exposed to the tubing pressure is generally designated 52, while the chamber 53 above the lower pumping piston 42 and below the divider 16 is generally designated 53, and is also directly exposed to the tubing pressure.

It will be noted that the unit is of a one-piece solid construction which can be lowered into or pulled out of the well without pulling the tubing. As an incident to lowering of the unit into the bottom of the well, the compression cup arrangement 18, 19 fits into and seals the opening in the compression cup holder 6, so as to prevent any liquid from escaping from the well casing or tubing 5 back into the well hole. As the unit seats on the bottom of the compression cup holder, previously identified anchoring means, 18, 19, 20, 21 anchor the unit in lowered position and prevent the friction of the compression cups in the unit from lifting the unit upwardly under operation of the pistons.

As the cable 22 is fastened in the element 24 on the upper pumping cylinder, when said cable is pulled upwardly, all of the described connected elements are pulled upwardly with respect to the upper and lower pump barrels 17 and 9 and thereby provide for passage of the liquid from the well into the chamber 50. The divider 16 is so arranged that a downward pressure is created below it in the lower pumping barrel 9 on the upstroke of the cable so as to cause a downward pressure to force the working parts of the unit downwardly after the surface power has pulled the same upwardly and let go.

As the cable 22 pulls the inner moving parts of the unit upwardly, liquid is forced out of the chamber 53 through the openings 15 in the slotted tubing 14 into the space 54 between the pumping unit and the well casing 5. As the movement starts, the check spool 26 in the upper pumping cylinder seats so as to close the opening 27 and thereby create a vacuum in the chamber 50. As the movement continues upwardly, pulling liquid through the bore of the tube 36, the spool check 33 is forced upwardly and unseated, thereby permitting the chamber 50 to fill. The compression cup assembly 39 seals the tubing 36 so that liquid in the chamber 53 cannot reach the chamber 50. These conditions obtain until the upper and lower pumping units have been pulled to the top of the stroke. As the surface machinery releases the tension on the cable 22, the fluid pressure exerted on the lower pump-

ing unit 42 through the openings 15 in the element 14, which is the full pressure of the liquid in the tubing 5, forces the lower pumping unit and hence the upper pumping unit downwardly. This creates a pressure in the chamber 50 which forces the spool check 33 to seat, or close, and forces the spool check valve 26 to an open position, thereby permitting liquid in the chamber 50 to flow out through the opening 26 in the upper pumping cylinder and into the chamber 52 which is exposed to the liquid in the tubing 5. Thus, the liquid is forced upwardly through the tubing.

It may be explained, at this point, that the previously identified anchoring means are constructed and arranged so that when the unit is being removed from the tubing, the upper pumping cylinder 25 releases the anchoring means, thereby releasing the unit as a whole for movement relative to the tubing 5, so that the entire unit can be hoisted or pulled out of the tubing 5, as occasion may require.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In a well pumping unit including a casing, an elongated barrel in the lower part of the casing spaced therefrom to form an annular space between said casing and barrel, both ends of the barrel being open, a divider dividing the barrel into upper and lower chambers, an upper piston in the upper chamber, a lower piston in the lower chamber, the bottom of the lower piston being open, means for closing the lower end of the annular space, packing means between each piston and the barrel, a valve cage connected with the lower end of the upper piston and having holes therein communicating the interior of the cage with the upper chamber, the upper piston having openings therein for communicating the upper portion thereof with the upper end of the barrel and said upper piston having an opening in its lower end communicating the piston with the cage, a downwardly closing valve in the upper piston controlling the opening in the bottom thereof, a tube connecting the lower end of the cage with the upper end of the lower piston for the passage of fluid from the lower piston into the cage, a downwardly closing valve in the cage for controlling communication between the interior of the cage and the tube, means connected with the upper end of the upper piston for moving the two pistons and the tube upwardly, the barrel having openings therein below the divider for admitting fluid from the annular space into the lower chamber to cause pressure of the fluid to act upon the lower piston to lower the piston assembly when said means is slackened.

2. In a well pumping unit including a casing, an elongated barrel in the lower part of the casing spaced therefrom to form an annular space between the casing and barrel, both ends of the barrel being open, a divider dividing the barrel into upper and lower chambers, an upper piston in the upper chamber, a lower piston in the lower chamber, the bottom of the lower piston being open, means for closing the lower end of the annular space, a valve cage connected with the lower end of the upper piston and communicat-

ing with the upper chamber, the upper piston having openings therein for communicating the upper portion thereof with the upper end of the barrel, and said upper piston having an opening in its lower end communicating the piston with the cage, a downwardly closing valve in the upper piston controlling the opening in the bottom thereof, a tube connecting the lower end of the cage with the upper end of the lower piston for

the passage of fluid from the lower piston into the cage, a downwardly closing valve in the cage for controlling communication between the interior of the cage and the tube, the barrel having openings therein below the divider for admitting fluid from the annular space into the lower chamber to cause pressure of the fluid to act upon the lower piston to lower the piston assembly.

BEE HENDERSON.
